MINING MACHINE

Morris P. Holmes, Claremont, N. H., assignor to
Sullivan Machinery Company, a corporation of
Massachusetts

Application March 26, 1930. Serial No. 439,186

12 Claims. (Cl. 262—30)

This invention relates to mining machines and more particularly to improvements in feeding mechanisms of such machines.

An object of this invention is to provide an improved mining machine feeding mechanism. Another object is to provide an improved flexible feeding mechanism for a coal mining machine, wherein a feed operating member cooperating with a flexible feeding element is utilized for feeding the machine and has associated therewith improved mechanism for controlling said feed operating member. Another object is to provide in a flexible feeding mechanism of the aforesaid character an improved clutch and brake mechanism for controlling the feed operating member whereby the latter may be entirely disconnected from its drive and frictionally held against rotation as desired. Yet another object is to provide an improved clutch and controlling brake respectively operative to entirely disconnect the feed operating member from its drive and frictionally resist rotation of said feed operating member. These and other objects and advantages of this invention will, however, hereinafter more fully appear.

In the accompanying drawing there is shown for purposes of illustration one form which the invention may assume in practice.

In the drawing,—

Fig. 1 is a plan view shown partially in horizontal section of the illustrative embodiment of the improved feeding mechanism.

Fig. 2 is a side elevational view of a portion of the mechanism shown in Fig. 1, parts being shown in section to illustrate structural details.

Fig. 3 is a detail sectional view illustrating the improved clutch mechanism, the clutch being shown in its connected position.

Fig. 4 is a view similar to Fig. 3 showing the clutch in its released position.

In this illustrative construction there is shown a flexible feeding mechanism of the same general character as that disclosed in my copending application, Ser. No. 367,894, filed June 3, 1929 and having incorporated therein the improved feed operating member controlling and braking means. As described in the aforesaid application, the feeding mechanism generally comprises a feed frame 1 having journaled thereon independently rotatable feed operating and controlling members 2 and 3, herein in the form of cable winding or haulage drums. Mechanism driven by a motor 4 is provided for effecting drive of the feed drums in winding direction either separately or simultaneously at relatively high speed or at relatively

low speed. The specific plural speed transmission connection between the motor and each of the drums is substantially of the same construction so that the description of the drive for one drum will suffice. As illustrated, secured to the motor shaft 5 is a spur pinion 6 driving through an intermediate gear 7 a gear 8 fixed to a horizontal longitudinally extending transmission shaft 9. Fixed to the shaft 9 in longitudinally spaced relation and driven thereby are coaxial worms, 65 one of which is indicated at 10. This worm 10 meshes with a worm wheel 11 fixed to a vertical shaft 12 which drives a worm 13 meshing with a slow speed worm wheel 14 which, as shown in Fig. 1, is journaled on a transverse shaft 15. 70 Fixed to the shaft 15 is a spur pinion 16 meshing with an internal gear 17 connectible, in an improved manner as hereinafter described, to the feed drum. The other coaxial worm (which is not shown in the drawing) meshes directly with 75 a fast speed worm wheel 18 likewise journaled on the transverse shaft 15. These worm wheels 14 and 13 are alternatively connectible with the shaft 15 by multiple disc clutches 19 and 20 respectively, having suitable operating mechanism 80 such as that disclosed in the application mentioned above. It will thus be seen that when the drum is connected in driving relation with the shaft 15 and one or the other of the disc clutches 19, 20 is applied, the feed drum may be driven 85 in winding direction at either a high or a low speed.

In the feeding mechanism disclosed in my copending application Ser. No. 367,894 it was found that under actual operating conditions, even 90 when the disc clutches of the feeding mechanism were released, there was sufficient adhesion or drag of the friction discs to cause the transverse shafts connected to the drums to tend to rotate by power and preventing completely free rotation 95 of the drums, and under certain conditions, for instance when the driving motor was reversed, causing the feed drums to creep and unwind their respective feed cables, with the risk of causing the feed cables to become twisted and 100 tangled. To overcome this disadvantageous feature, an improved main feed drum controlling clutch is provided to disconnect the drums from the friction clutches, together with improved frictional retarding means for preventing idle 105 rotation of the drums. Again referring to Fig. 1, it will be noted that the drum 3 is journaled on a cylindrical support member 21 which, as is hereinafter described, forms a drive element; and when the drum is disconnected from the mem- 110

ber 21, the drum is entirely relieved of any action of the disc clutches and free to rotate relative to this member. In the present construction, the member 21 is rigidly secured to the internal gear 5 17 and is journaled on anti-friction bearings supported by a stub shaft 22 projecting laterally from the side of the feed frame and retained in position on the stub shaft by devices indicated at 23. In the improved construction, formed on the 10 drive member 21 are projecting lugs 24, 25 having aligned perforations or bores extending perpendicularly to the axial line of the drum. Rotatably mounted within the bores formed in these projecting lugs is a cylindrical clutch bar or pin 26 having projecting end portions 27 preferably of 15 semi-circular cross section forming clutch elements engageable with notches or slots 28 formed in the outer face of the feed drum hub. As shown, this rotary clutch pin is maintained against axial 20 displacement from the lug bores by a spring pressed ball and groove connection 30 and has secured thereto intermediate its ends an annular collar member or sleeve 31 interposed between the inner faces of the lugs 24, 25. This sleeve or 25 collar is maintained in position with respect to the clutch pin 26 by a set screw 32 threadedly connected to the pin and extending through an aperture formed in the sleeve. This set screw has an enlarged rectangular head portion 33 30 which forms a handle for rotating the clutch pin to bring the semi-circular clutch portions 27 thereof into and out of the slots 28 on the drum. The cylindrical drive member 21 and the drum hub are transversely slotted at 33^a to form recesses in which the set screw is disposable in the 35 different positions of the clutch pin, thereby eliminating all protruding parts on the outer face of the drum. When the clutch pin 26 is in the position shown in Figs. 1 and 2 with the feed 40 drum locked to the cylindrical drive member 21 the semi-circular clutch portions 27 thereof are disposed (as clearly shown in Fig. 3) in the slots 28 in the drum hub. When the clutch pin is in its released position, that is in the position opposite 45 from that shown in Figs. 1 and 2, the semi-circular clutch portions of the pin lie entirely outside of the slots 28 as shown in Fig. 4, thereby entirely releasing the drum from the cylindrical drive member 21 and permitting the drum to 50 freely rotate.

It has been found that under certain conditions when the drum clutch was released, entirely disconnecting the drum from its drive, there was sufficient friction between the drum and the cylindrical member upon which it is supported as to cause the drum to creep and in case the direction of motor rotation was reversed, the feed cable would tend to unwind from the drum. To overcome this undesirable creeping action, there is 55 provided a frictional resistance device indicated generally at 34 and comprising a segmental brake band 35 pivotally connected at 36 to the side of the machine frame at the lower part of the drum, and extending, as shown in Fig. 2, partially 60 around the periphery of the internal gear 17. The free end of this brake band has secured thereto ears 37 pivotally connected at 38 to an operating lever 39. Pivotally connected at 40 on the side of the machine frame and extending 65 through an aperture in a rotary pin 41 carried by the lever 39 is a bolt 42, and interposed between a nut 43 and the pin 41 and encircling the bolt is a coil spring 44 which is adapted to yield upon a predetermined loading of the brake. The tension of the spring is made sufficient to cause the 70

brake to overcome the normal creeping tendency of the drum.

The operation of the improved feeding mechanism will be clearly apparent from the description given. Briefly, to summarize, the operation is as follows: When it is desired to effect power rotation of the drum in winding direction at either a higher or a low speed, the operator manipulates the handle 33 of the clutch pin 26, thereby turning the latter into a position to position the semicircular clutch portions 27 thereof within the slots 28 in the drum hub, and upon application of one or the other of the disc clutches 19, 20 the drum may be driven by the motor at either speed desired to effect winding in of its 80 cooperating cable. If it is desired to freely rotate the drum relative to its drive mechanism, for instance if it is desired to unwind the cable by hand, the disc clutches 19 and 20 are thrown into their released position and upon rotation of the 85 clutch pin 27, from the position shown in Fig. 3 to the position shown in Fig. 4, the drum is entirely disconnected from the cylindrical drive member 21, thereby entirely relieving the drum from any action of the disc clutches. It is then 90 possible to freely unwind the cable from its drum without the necessity of unwinding the drum against the drag of the clutch discs, which, as mentioned above, is present to some extent even when these clutches are released. If it is desired 95 to hold the drum against rotation when it is disconnected from its drive mechanism, for instance to hold the drum against creeping, this may be accomplished simply by swinging the brake lever 39 to throw the bolt 42 past the center of the 100 pivot 38, thereby applying the brake 35 and locking it, due to the relation of the pivots 38, 40 and 41, in its applied position.

As a result of this invention it will be noted that an improved flexible feeding means is provided 115 wherein the feed drum may be entirely disconnected from its drive mechanism and, when any creeping tendency occurs, may be frictionally held against rotation. It will further be noted that an improved main feed drum clutch is provided 120 which may operate by a simple swinging motion of a lever and which is extremely compact, being readily adapted for application to a standard feeding mechanism with a minimum of change. It will further be noted that an improved main 125 feed clutch is provided which comprises a relatively small number of parts and which is an extremely rugged design. It will still further be noted that an improved drum controlling mechanism is provided for a mining machine feeding 130 mechanism wherein all tendency of rotation of the drum, even when disconnected from its drive mechanism, is eliminated, the drum having associated therewith a frictional retarding device and clutch mechanism whereby the drum may be 135 entirely disconnected from its drive mechanism and held against undesired rotation.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by 140 Letters Patent is:

1. In a mining machine feeding mechanism, the combination of a feed member, driving mechanism therefor including a final driving element on which said feed member is rotatably mounted, 150

- a friction controlling clutch, and transmission gearing in the drive between said final driving element and said clutch and controlled by the latter, means for disconnecting said feed member from said final driving element entirely to relieve the same from the drag friction of the driving gearing and clutch, and associated means for preventing free rotation of said feed member when so disconnected, said latter means being automatically releasable upon a predetermined load to prevent complete braking of said feed member during normal operation of the feeding mechanism. 5
2. In a mining machine feeding mechanism, the combination of a feed member, driving mechanism therefor including a final driving element on which said feed member is rotatably mounted, a multiple disc controlling clutch, and transmission gearing in the drive between said final driving element and said clutch and controlled by the latter, means for disconnecting said feed member from said driving element entirely to relieve the same of any action of the driving gearing and clutch discs, and associated means for preventing free rotation of said feed member when so disconnected and including a brake element for resisting rotation of said feed member and yieldable loading means therefor automatically releasable to preclude complete braking of said feed member during normal operation of the feeding mechanism. 10
3. In a mining machine feeding mechanism, the combination of a feed member, and driving mechanism therefor including a final rotatable driving element on which said feed member is rotatably mounted, and means including a rotatable clutch element for connecting said feed member directly to or disconnecting the same from said driving element, said clutch element being rotatable with said driving element when in its disconnected position and rotatable relative to said driving element to effect connection and disconnection between the feed member and the driving element. 15
4. In a mining machine feeding mechanism, the combination of a feed member, and driving mechanism therefor including a final rotatable driving element arranged coaxially with said feed member and on which said feed member is rotatably supported, and clutch means operable at will to connect said feed member to or disconnect the same from said drive member and including a rotatable clutch element rotatable with said driving element when said clutch is disconnected and rotatable relative to said driving element to effect connection and disconnection between the feed member and the driving element. 20
5. In a mining machine feeding mechanism, the combination of a feed member, a drive member, and clutch means therebetween including a rotatable cylindrical clutch element having a cutaway end portion disposable to effect connection or disconnection of said members, and means for rotating said element on its axis to move said end portion into its connected and released positions. 25
6. In a mining machine feeding mechanism, the combination of a feed member, a drive member, and clutch means therebetween for connecting said members including a rotatable clutch element carried by said drive member, and means for rotating said element relative to said drive member into its connected and released positions. 80
7. In a mining machine feeding mechanism, the combination of a feed member, a drive member and clutch means therebetween including a rotary clutch element carried by said drive member and engageable with clutch elements carried by said feed member, and means for rotating said clutch element relative to said drive member into its connected and released positions. 85
8. In a mining machine feeding mechanism, the combination of a feed member, a drive member and clutch means therebetween for connecting said members to each other including a rotatable cylindrical clutch element carried in a bore formed in one of said members, and means for rotating said element on its axis into its connected and released positions. 90
9. In a mining machine feeding mechanism, the combination of a feed member, a drive member and clutch means therebetween for connecting said members to each other including a rotatable clutch element carried by one of said members and rotatable relative thereto about an axis transverse to the feed member axis, and means for rotating said element into its connected and released positions. 95
10. In a mining machine feeding mechanism, the combination of a feed member, a drive member and clutch means therebetween including a rotary cylindrical clutch element carried in a bore formed in one of said members and engageable with a clutch element carried by said other member to connect said members and means for rotating said rotary clutch element into its connected and released positions. 100
11. In a mining machine feeding mechanism, the combination of a feed member, a drive member and clutch means therebetween including a rotary clutch element carried by one of said members and engageable with a clutch element carried by said other member to connect said members, said clutch element being rotatable relative to the member which carries it about an axis transverse to the feed member axis, and means for rotating said rotary clutch element into its connected and released positions. 110
12. In a mining machine feeding mechanism, the combination of a feed member, a drive member, and clutch means therebetween for connecting said members including a rotatable clutch element carried by one of said members, and means for rotating said element relative to the member which carries it into its connected and released positions including a handle for rotating said clutch element, said handle being engageable in its different positions, with abutments formed on one of said members for limiting rotative movement of said clutch element. 115
13. In a mining machine feeding mechanism, the combination of a feed member, a drive member, and clutch means therebetween for connecting said members including a rotatable clutch element carried by one of said members, and means for rotating said element relative to the member which carries it into its connected and released positions including a handle for rotating said clutch element, said handle being engageable in its different positions, with abutments formed on one of said members for limiting rotative movement of said clutch element. 120
14. In a mining machine feeding mechanism, the combination of a feed member, a drive member, and clutch means therebetween for connecting said members including a rotatable clutch element carried by one of said members, and means for rotating said element relative to the member which carries it into its connected and released positions including a handle for rotating said clutch element, said handle being engageable in its different positions, with abutments formed on one of said members for limiting rotative movement of said clutch element. 125
15. In a mining machine feeding mechanism, the combination of a feed member, a drive member, and clutch means therebetween for connecting said members including a rotatable clutch element carried by one of said members, and means for rotating said element relative to the member which carries it into its connected and released positions including a handle for rotating said clutch element, said handle being engageable in its different positions, with abutments formed on one of said members for limiting rotative movement of said clutch element. 130
16. In a mining machine feeding mechanism, the combination of a feed member, a drive member, and clutch means therebetween for connecting said members including a rotatable clutch element carried by one of said members, and means for rotating said element relative to the member which carries it into its connected and released positions including a handle for rotating said clutch element, said handle being engageable in its different positions, with abutments formed on one of said members for limiting rotative movement of said clutch element. 135

MORRIS P. HOLMES.
